UNITED STATES PATENT OFFICE.

ROBERT L. COONEY, OF ATLANTA, GEORGIA.

STATIONARY FIRE-EXTINGUISHER SYSTEM.

1,244,293.

Specification of Letters Patent. Patented Oct. 23, 1917.

Application filed March 20, 1917. Serial No. 156,085.

To all whom it may concern:

Be it known that I, ROBERT L. COONEY, a citizen of the United States, residing at Atlanta, in the county of Fulton and State 5 of Georgia, have invented new and useful Improvements in Stationary Fire-Extinguisher Systems, of which the following is a specification.

This invention relates to improvements in 10 stationary fire extinguisher systems of that type wherein the operation of the system responds to and is initiated by a pressure disturbance developed in the distributing line.

15 For the operation of systems of the type stated, it has been proposed to fill the leaders or laterals with a non-freezing fire extinguishing liquid, a two-fold advantage being thereby secured, viz: the fire extinguishing 20 liquid is discharged immediately upon the opening of the sprinkler head and prior to the operation of the automatic devices, and the venting of the said liquid from a particular leader or lateral automatically develops 25 a suction impulse to which the automatic devices, for example, chemical mixing devices, are responsive; and to transmit the said suction impulse to the automatic devices by a suction pipe suitably related to the distributing system.

Heretofore, in order to eliminate any substantial air space in the distributing system with a consequent tendency to the attenuation 35 of the suction impulse and resultant uncertainty or delay in the operation of the system, the riser from the tank has been filled with non-freezing liquid and an automatic check valve has been employed to support the column of liquid in the riser 40 and to prevent said liquid from flowing into the tank. This check valve is objectionable in a number of respects, principally, because it is uncertain and difficult to set.

The object of the present invention is to 45 provide a fire extinguisher system wherein the pneumatic impulse may be developed by the discharge from the open sprinkler head of liquid normally stored in the leaders or laterals as heretofore but wherein the 50 complicating feature of the automatic check valve is wholly avoided and at the same time provision is made against the attenuation of the suction impulse in consequence of any extensive air space in the distributing 55 system.

An embodiment of the invention is illus-

trated in the accompanying drawing which comprises a single figure showing in vertical sectional diagram a system in which the features of the invention are incorporated. 60

The invention is disclosed in its application to a chemical mixing system, wherein the principal supply of fire extinguishing liquid is derived from a tank 1 containing an alkaline solution with which a supply of acid 65 maintained in a receptacle 2 is mixed to develop pressure for forcing the fire extinguishing liquid through the distributing system. The distributing system includes a riser 3 whose lower portion projects into the tank 2 70 nearly to the bottom thereof. The said riser extends to the top of the building to be protected, and according to the present invention is connected with a vertical supply pipe 4 from which extend, in the usual manner, 75 the various leaders or laterals 5, each equipped with suitable sprinkler heads or distributing valves 6. The pipe 4 and the leaders or laterals 5 are normally filled with a non-freezing fire extinguishing liquid. 80

The suction impulse by which the operation of the system is automatically initiated is transmitted by a pipe 7. The mixing of the chemicals may be effected in any desired manner and the invention is, therefore, not concerned with the particular construction and arrangement of the acid bottle 2. For example, the acid bottle may, as shown, be of the well known invertible type, discharging 90 its contents consequent to its inversion, or a syphonic discharge of the acid may be employed, as shown, for example, in the patent to Thompson No. 1,206,173. The invertible acid bottle 2 shown in the drawings is pivotally supported below center by 95 brackets 8. Said bottle may normally be held in an upright position by the device shown in my prior Patent No. 1,075,018 which comprises a latch pin 9 engaging the top of said acid bottle, a pressure operated plunger 10 carrying said latch pin, and a cylinder 11 in which the plunger 10 is movable. In the embodiment disclosed, the cylinder 11 is secured at the lower end of the pipe 7 and the plunger 10 is provided with 100 a pressure equalizing pin-hole 12.

According to the present invention, a suction chamber 13 is provided at the upper end of the pipe 4, said chamber having at one side thereof a domed extension 14 into 110 which a vertical leg 15 of the pipe 7 projects. The riser 3 is connected at its upper

end to the chamber 13 by a U-shaped pipe 16 which provides a trap and normally contains a body of liquid 17 constituting a water seal. The pipe 16 has a filling aperture 18 normally closed by a cap or plug 19 and at its lowest point is provided with a drain cock 20.

The object of the water seal between the chamber 13 and the riser 3 is to prevent the air in said riser from attenuating the suction impulse developed by the discharge of the non-freezing fire extinguishing liquid from an open sprinkler head and transmitted by the pipe 7 to the plunger 10.

In the operation of the system, the suction impulse developed in the chamber 13 is transmitted by the pipe 7 to provide for the chemical mixing operation. In the present embodiment, this is effected by an upward movement of the plunger 10 in consequence of the greater pressure acting at the time of the suction influence on the under face of said plunger. Upon the disengagement of the pin 9 from the bottle 2, said bottle over-turns by gravity and its acid contents mixes with the solution in the tank 1, the liquid being forced from said tank by the developed high pressure. When the pressure is developed in the tank 1, the liquid flows through the riser 3, the pipe 16 and the chamber 13 into the pipe 4 and thence to the leader or lateral of the open sprinkler head. The extension 14 of the chamber 13 provides for the development of an air cushion or seal which prevents the liquid from flowing into the end of the pipe 7.

I claim as my invention—

1. In a fire extinguisher system of that type which includes a tank, a riser extending from the tank, means coöperating with the tank for supplying fire extinguishing liquid and a pipe for transmitting a suction impulse to initiate the operation of said

means, a vertical liquid-containing pipe to which the leaders are connected, a suction chamber at the upper end of the vertical pipe and to which said impulse-transmitting pipe is connected, and a water seal maintaining connection between the upper end of said riser and said suction chamber. 45

2. In a fire extinguisher system of that type which includes a tank, a riser extending from the tank, means coöperating with the tank for supplying fire extinguishing liquid and a pipe for transmitting a suction impulse to initiate the operation of said means, a vertical liquid-containing pipe to which the leaders are connected, a suction chamber at the upper end of the vertical pipe and to which said impulse-transmitting pipe is connected, and a U-shaped pipe connecting said suction chamber and the upper end of said riser. 50

3. In a fire extinguisher system of that type which includes a tank, a riser extending from the tank, means coöperating with the tank for supplying fire extinguishing liquid and a pipe for transmitting a suction impulse to initiate the operation of said means, a vertical liquid-containing pipe to which the leaders are connected, a suction chamber at the upper end of the vertical pipe, a water seal maintaining connection between the upper end of said riser and said suction chamber, and a domed extension at one side of said suction chamber into which a vertical leg of said impulse-transmitting pipe projects. 65

In testimony whereof I have hereunto set my hand in presence of two subscribing witnesses. 80

ROBERT L. COONEY.
